UNITED STATES PATENT OFFICE.

ALFRED A. LAUTERNIER, OF LIMOGES, FRANCE.

DESIGN FOR A DISH.

SPECIFICATION forming part of Design No. 21,388, dated March 8, 1892.

Application filed February 12, 1892. Serial No. 421,332. Term of patent 3½ years.

To all whom it may concern:

Be it known that I, ALFRED A. LAUTERNIER, a citizen of France, residing at Limoges, in the Republic of France, have invented and produced a new and original Design for Table-Ware, of which the following is a specification.

In the accompanying drawing a face view of a plate embodying my new design for dishes is shown.

The essential features of my design consist of a border for the dishes, composed of a series of segmental sections, between which shell-shaped sections are arranged, the segmental sections having a slightly-scalloped outer edge and an arabesque leaf ornament along the inner edges. In said segmental sections grooves are formed, which extend from the outer edge and gradually disappear toward the center of the section. The shell-shaped sections between the segmental sections are surrounded by an arabesque leaf ornament, and each shell-shaped section is provided with a scalloped surface ornamentation.

A are the segment-sections of the border; B, the shell-shaped sections between them.

A represents the slightly-scalloped border of the sections A, and *d* the arabesque leaf ornament along the inner edges of said section. 30

e are the grooves extending from the scalloped outer edges of the sections A toward the center, where they disappear.

f are depressions along the inner edges of the sections A. 35

g represents the arabesque leaf ornament along the edges of the shell-shaped sections B.

I claim—

The design for a dish, substantially as herein shown and described. 40

In testimony that I claim the foregoing as my own I have signed my name in presence of two subscribing witnesses.

ALFRED A. LAUTERNIER. [L. s.]
